UNITED STATES PATENT OFFICE.

EDWARD COOPER SEARLE, OF HILO, TERRITORY OF HAWAII.

HEADLIGHT.

Application filed August 22, 1922. Serial No. 583,577.

To all whom it may concern:

Be it known that I, EDWARD C. SEARLE, a citizen of the United States, and a resident of Hilo, in the Territory of Hawaii, have invented a new and Improved Headlight, of which the following is a full, clear, and exact description.

This invention relates to improvements in headlights, and more particularly to a headlight or attachment for headlights, designed to prevent glare, an object of the invention being to provide a conical or tapering light directing shield which will direct a bolt of light to illuminate the road ahead and deflect light on the ground, but which will prevent a spread of light or rather prevent the divergence of rays of light to an extent to cause glare to an approaching car.

A further object is to provide a headlight of the character described which can be used in connection with headlight mounts in ordinary use, and which can be manufactured and sold at a reasonably low price.

With these and other objects in view, the invention consists in certain novel features of construction and combinations, and arrangement of parts, as will be more fully hereinafter described and pointed out in the claim.

In the accompanying drawings, Figure 1 is a view in longitudinal section illustrating my improved headlight.

Figure 2 is a view in front elevation of Figure 1.

1 represents a lamp shell having a stationary lamp socket 2 therein, and 3 represents a reflector spaced from the shell and having an annular flange 4 at its outer edge secured to the annular flange 5 of the shell, as will more fully hereinafter appear. A disk or plate of glass 6 is located against the flange 4 of reflector 3, and my improved conical shield 7 is positioned in front of the glass 6 and has an annular flange 8 located against the glass 6. The flanges 4, 5 and 8 are all perforated to receive clamping bolts, or screws 9, which are secured by nuts 10 to clamp the parts together.

11 represents a lamp preferably of the

electric incandescent type having a lug 12 fixed thereto and provided with a screw threaded opening 13, receiving an adjusting screw 14 mounted in a lug 15 on the shell 1 and having a head 16 at its rear end for the reception of the screw driver to adjust the screw and change the position of the lamp to adjust the focus thereof.

The shield 7 above referred to, is of largest diameter at its rear end and tapers toward its forward end, where it is provided with an opening 17, or transparent portion, or any suitable form of lens to permit a bolt of light to be thrown forwardly to illuminate the road, but confined in diameter so as to prevent glare to those in 63 the driver's seat of approaching vehicle.

The shield 7 is provided in the lower portion of its sides with elongated triangular openings 18, although of course, it is to be understood that these openings may have 70 transparent portions therein if desired. The openings 18 are formed by stamping sections 19 therefrom which are bent outwardly and form outwardly and downwardly deflecting plates to direct the light along the road, 75 ahead of the headlight, but prevent upward reflection.

It will be noted that my improved shield may be attached to ordinary headlights, but is preferably adapted for use in connection 80 with the structure illustrated where the lamp 11 is capable of longitudinal adjustment for necessary focusing.

The interior of the shield 7 serves as a reflector, which co-operates with the reflector 3 to direct the rays of light in a small bolt forwardly and in a large lateral direction. This latter direction being downwardly as well as forwardly to give the proper road illumination in front of the car. 85

The shield 7 is preferably of metal and opaque although it may be made of any suitable material, and I do not wish to be limited in this respect.

Various slight changes might be made in the general form and arrangement of parts described without departing from my invention, and hence I do not limit myself to

the precise details set forth, but consider myself at liberty to make such changes and alterations as fairly fall within the spirit and scope of the appended claim.

I claim:

A shield of the character described of general tapering form, having a light passage

in its smaller end, having light passages in its sides, and fixed plates constituting reflectors and located above the side light passages and inclined downwardly and outwardly from. 10

EDWARD COOPER SEARLE.
